UNITED STATES PATENT OFFICE.

ADOLPH WUNDER, OF NEW HAVEN, CONNECTICUT, ASSIGNOR TO SARGENT & CO., OF SAME PLACE.

DESIGN FOR A BASE FOR BIRD-CAGE BRACKETS.

Specification forming part of Design No. 5,287, dated September 26, 1871.

To all whom it may concern:

Be it known that I, ADOLPH WUNDER, of New Haven, in the county of New Haven and State of Connecticut, have invented a new and original Design for Base for Bird-Cage Bracket; and I do hereby declare the following, when taken in connection with the accompanying drawing and the letters of reference marked thereon, to be a full, clear, and exact description, and which said drawing constitutes part of this specification, and represents a front view of the base.

This invention relates to a design in that class of brackets known to the trade as bird-cage brackets—that is, a plate or base from which a hooked arm extends, by means of which a bird-cage or other article may be suspended; and the design consists in the peculiar configuration and

ornamentation shown in the accompanying illustration and hereafter described.

The plate is, by preference, cast. Around the edge a narrow plain border is raised and on the surface tracery, substantially as shown, so that the tracery and border may be polished, leaving the remaining surface "dead;" and this may be matted or otherwise treated.

I claim—

The design for base for bracket, substantially as described and shown in the accompanying illustration.

ADOLPH WUNDER.

Witnesses:

C. W. BURDETT,
CHAS. L. BALDWIN.
